UNITED STATES PATENT OFFICE.

PAUL C. SCHROEDER, OF CHICAGO, ILLINOIS, ASSIGNOR TO SEARS, ROEBUCK AND COMPANY, OF CHICAGO, ILLINOIS, A CORPORATION OF NEW YORK.

TRUNK.

1,189,390.

Specification of Letters Patent.

Patented July 4, 1916.

Application filed April 9, 1915. Serial No. 20,126.

To all whom it may concern:

Be it known that I, PAUL C. SCHROEDER, a citizen of the United States, residing at Chicago, in the county of Cook and State 5 of Illinois, have invented certain new and useful Improvements in Trunks, of which the following is a specification.

The object of this invention is to produce an improved trunk in which the walls are 10 reinforced at their edges and corners so as to to produce a strong and rigid structure capable of withstanding severe strains and shocks.

In the accompanying drawings, Figure 1 15 is a perspective view of a trunk embodying the features of my invention, the view showing merely the plain body of the trunk, without the covering material or any of the usual furnishings. Fig. 2 is a transverse 20 vertical section through the trunk. Fig. 3 is an interior view of one corner, the view being a section taken approximately in the plane of line 3—3 of Fig. 1. Fig. 4 is a sectional detail view illustrating the manner in 25 which the edges of the walls are reinforced. Fig. 5 is a fragmentary view of one corner of the trunk showing a portion of one wall and its reinforcing strip spaced away from the other parts to better illustrate their 30 relation. Figs. 6, 7 and 8 are detail views of the end portions of three reinforcing strips which abut at each of the corners of the trunk.

Each of the walls 10 is rabbeted on its 35 inner face, as indicated at 11, along all four of its edges. The meeting edges of any two adjacent walls overlap each other, and in the corner formed by the walls or in the two merging rabbets is fitted the square 40 corner of a reinforcing strip 12 of triangular form, the two acute angles of the strip preferably being flattened off, as indicated at 13, to abut squarely against the shoulders 14 formed by the rabbets. The diagonal 45 faces of the strips are adjacent to the interior of the trunk. Each of the strips 12 is firmly glued to the walls 10, and in addition a suitable number of fastening devices

15 are employed to secure the strips rigidly in place. The vertical walls of the trunk 50 and the vertical reinforcing strips 12 are divided along a horizontal line 16 to provide the body section and the lid section of the trunk which are suitably hinged together. 55

At each corner of the trunk the ends of the three reinforcing strips are shaped so as to fit close together and form a strong rigid joint. This is done preferably by providing a square or perpendicular end face 17 on 60 one of the strips which abuts squarely against the opposing trunk wall; by forming a single beveled face 18 on the end of another of the strips which face is adapted to abut against the diagonal face of the first 65 mentioned strip; and by forming two beveled faces 19, or in other words providing a wedge-shaped end, upon the third strip, which end is adapted to abut snugly 70 against the two diagonal faces of the first 75 mentioned strips. The joint thus formed is strong and rigid and is capable of withstanding severe strains. Preferably the reinforcing strips are made of harder or tougher wood than that of which the walls 10 are formed, for the purpose of insuring greater 80 rigidity.

I claim as my invention:

A trunk comprising walls, reinforcing strips fixed in the angles between adjacent 80 walls, the end portions of the three strips at each corner of the trunk being shaped to abut against each other and provide a rigid joint, one of the strips having a perpendicular end abutting against the opposing wall, another of the strips having a single bevel end to abut against the first strip, and the third strip having a double bevel or wedge-shaped end to abut against both of the two first mentioned strips. 85 90

In testimony whereof, I hereunto set my hand in the presence of two witnesses.

PAUL C. SCHROEDER.

In the presence of

C. J. CORNWELL,

E. L. CURTIS.
